MIXING OR DETECTOR CIRCUIT

Gesinus Diemer and Kornelis Swier Knol, Eindhoven, Netherlands, assignors to Hartford National Bank and Trust Company, Hartford, Conn., as trustee

Application April 29, 1949, Serial No. 90,422
In the Netherlands May 14, 1948

7 Claims. (Cl. 250—20)

1

The present invention relates to mixing or detector circuits comprising means by which the phase angle of the mutual conductance is continuously varied during each cycle of the local oscillations. Use may be made of a so-called transit-time tube, in which the deflection of an electron beam is controlled under the action of the local oscillations and of the incoming wave, the beam ultimately striking one or more anodes from which the intermediate frequency output voltage is taken.

This improved circuit-arrangement is characterized in that in the discharge tube wherein the electron beam is produced and which comprises a system for the deflection of the beam, which system is influenced both by the incoming wave and by the wave produced locally, the beam is deflected in two different coordinate directions with different phases and, upon deflection, strikes an anode consisting at least of two parts and to which the output circuit is connected, the control of the beam and the construction of the anode being such that if exclusively the signal wave or the locally produced wave exercises a deflecting influence, no alternating current appears in the output circuit, whereas in the case of deflection by both waves simultaneously a current of the difference frequency appears in the output circuit.

The arrangement is preferably such that the point of impact of the beam on the anode, in the absence of a signal voltage, moves approximately along a closed curve constituting the line of demarcation between the two anode parts.

In order that the invention may be more clearly understood and readily carried into effect it will now be described more fully with reference to the accompanying diagrammatic drawing, given by way of example.

In Fig. 1, the reference numeral 1 designates a cathode, 2 denoting an element by which the electrons emitted by the cathode are formed into a beam. This beam moves between the pairs of deflection electrodes 3—4, 5—6, 7—8 and 9—10 and eventually strikes an anode consisting of two annular parts 11 and 12. These parts are insulated from one another and connected to the ends of a tuned circuit 13 which is tuned to the difference frequency of incoming oscillations and oscillations produced by a local oscillator, which circuit 13 is coupled to a circuit 14 which is also tuned to the said difference frequency. From the latter, the intermediate frequency oscillations are taken for further use.

Voltages, for instance of the local oscillator

frequency, which may be represented by $V_o \sin \omega_o t$ and $V_o \sin (\omega_o t + 90^\circ)$ are applied to the pairs of deflection electrodes 3—4 and 5—6 across the oscillatory circuits 16 and 17 tuned to the local oscillator frequency, so that the voltage set up at the electrodes 3—4 is displaced in phase by 90° with respect to the voltage set up at the electrodes 5—6. Similarly, voltages of the signal frequency, which may be represented by $V_s \sin \omega_s t$ and $V_s \sin (\omega_s t + 90^\circ)$ and consequently also displaced in phase by 90° with respect to one another, are applied to the electrodes 7—8 and 9—10 across the circuits 18—19 tuned to the signal frequency. The local oscillator voltage is chosen to be such that, in the absence of a signal voltage, the point of impact of the beam on the anode moves substantially along the circular line of demarcation 15 between the two parts 11 and 12. The appearance of a signal voltage at the electrodes 7—8 and 9—10 results in that the diameter of the circle along which the impact point moves, is varied periodically, the period of these variations being equal to the difference between the local oscillator frequency and the signal frequency, and the amplitude of the variations being equal to the radius of the circle described by the impact point if only the signal voltage were operative. Consequently, an intermediate frequency current may be taken from across the anode rings 11 and 12, the conversion mutual conductance corresponding to the static mutual conductance. Voltages of a frequency different from the difference frequency do not occur.

Fig. 2 represents a simplified circuit-arrangement comprising only two pairs of deflection plates 20—21 and 22—23. The voltages $V_o \sin \omega_o t$ and $V_s \sin \omega_s t$ set up in the circuits 16 and 18 are operative in series between plates 20 and 21. The circuits 17 and 19 in which the voltages $V_o \sin (\omega_o t + 90^\circ)$ and $V_s \sin (\omega_s t + 90^\circ)$ are operative are connected in series between plates 22 and 23. The remaining part of the arrangement corresponds to that shown in Fig. 1 and the operation of the circuit-arrangement is exactly similar.

The said arrangements may also be used for wave lengths exceeding 3 m.

What we claim is:

1. An electrical circuit arrangement for mixing a first wave and a second wave to produce an intermediate frequency wave, comprising an electron discharge tube comprising means to form an electron beam and to direct said beam along a given path, deflecting means arranged

about said given path for deflecting said beam in two coordinate directions and an anode structure comprising first and second conductive portions separated by an insulating path having the configuration of a closed curve, means to apply said first wave to said deflecting means to cause said beam to define a trace substantially coincident with said insulating path, means to apply said second wave to said deflecting means to cause said beam to impinge selectively on said first and second conductive portions of said anode structure at a frequency equal to said intermediate frequency, and an output circuit coupled to said anode structure.

2. An electrical circuit arrangement for mixing a first wave and a second wave to produce an intermediate frequency wave, comprising an electron discharge tube comprising means to form an electron beam and to direct said beam along a given path, deflecting means arranged about said given path for deflecting said beam in two coordinate directions and an anode structure comprising first and second annular conductive portions separated by a continuous insulating path, means to apply said first wave to said deflecting means to cause said beam to define a trace substantially coincident with said insulating path, means to apply said second wave to said deflecting means to cause said beam to impinge selectively on said first and second conductive portions of said anode structure at a frequency equal to said intermediate frequency, and an output circuit coupled to said anode structure.

3. An electrical circuit arrangement for mixing a first wave and a second wave to produce an intermediate frequency wave, comprising an electron discharge tube comprising means to form an electron beam and to direct said beam along a given path, first, second, third and fourth pairs of deflecting elements arranged about said given path for deflecting said beam in two coordinate directions and an anode structure comprising first and second annular conductive portions separated by a continuous insulating path, means to apply said first wave to said first pair of deflecting elements in a first given phase and to said second pair of deflecting elements in a second phase substantially in phase quadrature with said first given phase thereby to cause said beam to define a trace substantially coincident with said insulating path, means to apply said second wave to said third pair of deflecting elements in a third given phase and to said fourth pair of deflecting elements in a fourth phase substantially in phase quadrature with said third phase thereby to cause said beam to impinge selectively on said first and second conductive portions of said anode structure at a frequency equal to said intermediate frequency, and an output circuit coupled to said anode structure.

4. An electrical circuit arrangement for mixing a first wave and a second wave to produce an intermediate frequency wave, comprising an electron discharge tube comprising means to form an electron beam and to direct said beam along a given path, first, second, third and fourth pairs of deflecting electrodes arranged about said given path for deflecting said beam in two coordinate directions and an anode structure comprising first and second annular conductive portions separated by a continuous insulating path, means to apply said first wave to said first pair of deflecting electrodes in a first given phase

and with a first given amplitude and to said second pair of deflecting electrodes in a second phase substantially in phase quadrature with said first given phase and with a second given amplitude thereby to cause said beam to define a trace substantially coincident with said insulating path, means to apply said second wave to said third pair of deflecting electrodes in a third given phase and to said fourth pair of deflecting electrodes in a fourth phase substantially in phase quadrature with said third given phase thereby to cause said beam to impinge selectively on said first and second conductive portions of said anode structure at a frequency equal to said intermediate frequency, and an output circuit coupled to said anode structure.

5. An electrical circuit arrangement for mixing a first wave and a second wave to produce an intermediate frequency wave, comprising an electron discharge tube comprising means to form an electron beam and to direct said beam along a given path, first and second pairs of deflecting elements arranged about said given path for deflecting said beam in two coordinate directions and an anode structure comprising first and second annular conductive portions separated by a continuous insulating path, means to apply said first wave to said first pair of deflecting elements in a first given phase and to said second pair of deflecting elements in a second phase substantially in phase quadrature with said first given phase to cause said beam to define a trace substantially coincident with said insulating path, means to apply said second wave to said first pair of deflecting elements in a third given phase and to said second pair of deflecting elements in a fourth phase substantially in phase quadrature with said third given phase thereby to cause said beam to impinge selectively on said first and second conductive portions of said anode structure at a frequency equal to said intermediate frequency, and an output circuit coupled to said anode structure.

6. An electrical circuit arrangement for mixing a first wave and a second wave to produce an intermediate frequency wave, comprising an electron discharge tube comprising means to form an electron beam and to direct said beam along a given path, first and second pairs of deflecting electrodes arranged about said given path for deflecting said beam in two coordinate directions and an anode structure comprising first and second annular conductive portions separated by a continuous insulating path, means to apply said first wave to said first pair of deflecting electrodes in a first given phase and with a given amplitude and to said second pair of deflecting electrodes in a second phase substantially in phase quadrature with said first phase and with said given amplitude thereby to cause said beam to define a trace substantially coincident with said insulating path, means to apply said second wave to said first pair of deflecting electrodes in a third given phase and to said second pair of deflecting electrodes in a fourth phase substantially in phase quadrature with said third given phase thereby to cause said beam to impinge selectively on said first and second conductive portions of said anode structure at a frequency equal to said intermediate frequency, and an output circuit coupled to said anode structure.

7. An electrical circuit arrangement for mixing a first wave and a second wave to produce an intermediate frequency wave, comprising an

electron discharge tube comprising means to form an electron beam and to direct said beam along a given path, deflecting means arranged about said given path for deflecting said beam in two co-ordinate directions and an anode structure comprising first and second annular conductive portions separated by an annular insulating portion, means to apply said first wave to said deflecting means to cause said beam to define a circular trace substantially coincident with said insulating portion, means to apply said second wave to said deflecting means to cause said beam to impinge selectively on said first and second conductive portions of said anode structure at a frequency equal to said intermediate frequency, and an output circuit coupled to said anode structure. 15
